TELEVISION SIGNAL-TRANSLATING APPARATUS

John A. Rado, Douglaston, N. Y., assignor to Hazeltine Corporation, a corporation of Delaware

Application March 26, 1942, Serial No. 436,229

5 Claims. (CL 315—14)

This invention relates generally to focusing systems and, more particularly, to focusing systems of a type adapted for use in a television signal-translating apparatus including a cathode-ray type signal-translating device.

In television signal-translating apparatus of the cathode-ray type it is a common and necessary expedient to provide an arrangement for the purpose of focusing the electron beam of the cathode-ray tube. While known arrangements are generally effective to focus the electron beam of such signal-translating devices for constant operating conditions, it is found that the arrangements of the prior art are not able to maintain the focus of the electron beam substantially constant for varying or fluctuating operating conditions. This is especially true of those arrangements in which both the accelerating electrode system and the beam-focusing system of the cathode-ray device are energized from a common power-supply circuit. In general, the focus of the electron beam is determined by the energization of both of these systems and, hence, in the prior-art arrangements of the type under discussion, fluctuations in the voltage of the common supply circuit which cause corresponding variations in the energization of both of these units tend undesirably to vary the focus of the electron beam.

Since variations of the energization of the accelerating electrode system tend to vary the focus of the electron beam in one sense, while corresponding variations of the energization of the beam-focusing system tend to vary the focus of the beam in the opposite sense, there is a tendency for the variations to compensate one another. However, in known focusing arrangements the compensation is imperfect because a given voltage fluctuation of the common supply circuit generally causes the beam-accelerating electrode system and the beam-focusing system to effect focus variations of different magnitudes so that the beam is effectively defocused. Therefore, it is necessary in such prior-art arrangements to provide a manual adjustment in the beam-focusing system so that, when there is a fluctuation in the voltage of the common supply circuit which throws the electron beam out of focus, the energization of the beam-focusing system may be adjusted to reestablish proper beam focus. Such means for controlling the focus of the electron beam is undesirable in that it requires an additional manual control and does not automatically maintain the beam in constant focus under all operating conditions.

It is an object of the invention, therefore, to provide an improved beam-focusing system for a television signal-translating device of the cathode-ray type which avoids one or more of the above-mentioned disadvantages of the prior art.

It is a further object of the invention to provide an improved beam-focusing system for a television signal-translating apparatus of the cathode-ray type which maintains the focus of the electron beam substantially constant even though the voltage of the supply circuit of the apparatus tends to fluctuate and tends thereby to vary the focus of the electron beam.

In accordance with the present invention, a television signal-translating apparatus comprises a cathode-ray signal-translating device, an accelerating electrode system for the device having a predetermined voltage-focus characteristic, a beam-focusing system for the device having a predetermined voltage-focus characteristic, and a common supply circuit for the systems the voltage of which is subject to fluctuations. A plurality of magnetic focusing windings are included in the focusing system, the number of turns in each of the windings being such that the voltage-focus characteristics of the electrode system and the beam focusing system are so related that fluctuations in the voltage of the supply circuit cause the systems to effect substantially complementary variations in the focus of the beam whereby the focus of the beam is maintained substantially constant.

In accordance with a feature of this invention, the focusing windings of a magnetic beam-focusing arrangement which have predetermined current-focus characteristics are individually energized by way of circuit means having predetermined voltage-current characteristics whereby the focusing system is caused to have a predetermined voltage-focus characteristic related to that of the accelerating electrode system of the cathode-ray device.

For a better understanding of the present invention, together with other and further objects thereof, reference is had to the following description taken in connection with the accompanying drawing, and its scope will be pointed out in the appended claims.

In the accompanying drawing, the single figure 50 is a circuit diagram, partially schematic, of a complete modulated-carrier signal receiver embodying a preferred form of the present invention.

Referring now more particularly to the drawing, there is illustrated a television receiver of

the superheterodyne type including an antenna system 10, 11 connected to a radio-frequency amplifier 12 to which there is connected in cascade a plurality of signal-translating stages: namely, an oscillator-modulator 13, an intermediate-frequency amplifier 14, a detector and A. V. C. supply 15, a video-frequency amplifier 16, and a cathode-ray signal-reproducing device 17. A unidirectional voltage is derived from detector and A. V. C. supply 15 and applied to one or more of the tubes of radio-frequency amplifier 12, oscillator-modulator 13, and intermediate-frequency amplifier 14 to control the amplification of the signal-translating stages of the receiver and thereby maintain the signal input to detector 15 within a relatively narrow amplitude range for a wide range of received signal intensities. A scanning unit 18 which includes synchronizing-signal separating means and line-frequency and field-frequency scanning generators is coupled to the output circuit of the detector 15 and supplies scanning currents or voltages to the scanning elements of the cathode-ray device 17 by way of a line-scanning amplifier 19 and field-scanning amplifier 19'. A sound-signal reproducer 24 is coupled to an output circuit of intermediate-frequency amplifier 14 for translating and reproducing sound signals accompanying the received television program. Unidirectional operating potentials for the receiver are derived from a common power-supply circuit 20 and are applied, by way of a conductor 21, to the radio-frequency amplifier 12, the oscillator-modulator 13, the video-frequency amplifier 16, the scanning unit 18, and the line-scanning amplifier 19. The accelerating electrode system which, as will be disclosed more fully hereinafter, is included in the cathode-ray device 17, is energized from supply circuit 20 by way of conductor 22. Operating potentials are also applied from the supply circuit 20 to the intermediate-frequency amplifier 14, and to the field-scanning amplifier 19' in a manner to be described hereinafter. The supply circuit 20, in turn, is energized by way of a connection 23 from any suitable source of power. The stages of elements 12-20 and 24 of the receiver, as thus far described, may all be of conventional and well known construction so that detailed illustrations and descriptions thereof are deemed unnecessary herein.

Referring briefly, however, to the operation of the receiving system, television signals intercepted by the antenna circuit 10, 11 are selected and amplified in the radio-frequency amplifier 12 and supplied to the oscillator-modulator 13 wherein they are converted into intermediate-frequency signals which, in turn, are selectively amplified in the intermediate-frequency amplifier 14 and delivered to the detector 15. The modulation components of the signal are derived by the detector 15 and are supplied to the video-frequency amplifier 16 wherein they are amplified and from which they are supplied in the usual manner to a brilliancy-control electrode of a cathode-ray tube included in the cathode-ray signal-translating device 17. The intensity of the electron beam in the cathode-ray device 17 is thus modulated or controlled in accordance with the video-frequency voltages impressed upon the control electrode thereof in the usual manner.

The modulation components from detector 15 are also supplied to the synchronizing-signal separating apparatus included in unit 18 which, in turn, separates the synchronizing-signal components from the video-frequency components and applies these components to the control cir-

cuit of the line and field-scanning generators included in unit 18. Saw-tooth scanning waves are generated in the line-scanning and field-scanning generators of unit 18 and applied to the scanning amplifiers 19 and 19', respectively, from which they are applied to the scanning elements of the cathode-ray signal-translating device 17 to produce scanning fields, thereby to deflect the intensity-modulated ray in two directions normal to each other so as to trace successive fields of parallel lines on the screen of the tube to reproduce the transmitted picture. The A. V. C. control potential, derived from unit 18 and applied to one or more tubes of the preceding stages, serves to maintain the amplitude of the signal input to detector 15 within a relatively narrow range for a wide range of received signal amplitudes. Sound signals accompanying the received television program are reproduced in sound-signal reproducer 24 in a conventional manner.

Referring more particularly to that portion of the receiver which embodies the arrangement of the present invention for maintaining the focus of the electron beam of the image-reproducing device 17 constant, it may be seen that the reproducing device 17 comprises a conventional type of cathode-ray signal-reproducing tube 25 having an accelerating electrode system including an anode 26 for accelerating an electron beam in well-known manner. This electrode system has a predetermined voltage-focus characteristic, whereby variations in the operating potential applied thereto from supply circuit 20 cause predetermined variations in the focus of the electron beam.

A beam-focusing system of the magnetic type is provided for focusing the electron beam of cathode-ray tube 25 and comprises at least one but, preferably, a plurality of magnetic focusing windings having predetermined current-focus characteristics, whereby variations in the current in the focusing windings effect variations in the focus of the scanning beam. Thus, a first focusing winding 28 and a second focusing winding 29 are coaxially positioned about the neck of tube 25. As is to be presently described, the circuit means connecting the focusing windings with the common power supply 20 has such a predetermined voltage-current characteristic and the number of turns in the focusing windings is so selected that the focusing system is caused to have a predetermined voltage-focus characteristic related to that of the accelerating electrode system. Only those portions of the reproducing device 17 necessary to a complete understanding of the present invention have been shown. The remaining elements thereof are conventional and of well-known construction.

It will be understood that the excitation circuits of the several signal-translating stages 12-16, 18, 19 and 19', which are included in the receiver, have predetermined voltage-current characteristics and that, in general, these characteristics will not be the same. That is, a given fluctuation in the voltage of the supply circuit 20 causes widely different current variations in the excitation circuits of the several signal-translating stages. In accordance with the present invention, the several beam-focusing windings 28, 29 are connected to supply circuit 20 by way of the excitation circuits of those signal-translating stages of the receiver which have such predetermined voltage-current characteristics that the beam-focusing system is caused to have a predetermined voltage-focus characteristic so re-

lated to that of the accelerating electrode system that voltage fluctuations of the supply circuit so cause the systems to effect substantially complementary variations on the focus of the electron beam. In the specific embodiment of the invention under consideration, winding 28 is connected in series in the circuit for supplying a unidirectional operating potential to the intermediate-frequency amplifier 14 from the supply circuit 20, and winding 29 is connected in series in the circuit for supplying a uni-directional operating potential to the field-scanning amplifier 19' from the supply circuit 20.

In considering the operation of the arrangement just described, it will be understood that the voltage of the supply circuit 20 is subject to fluctuations which vary the energization of both the accelerating electrode system and beam-focusing system of the receiver and tend thereby undesirably to vary the focus of the electron beam. However, the voltage-current characteristic of the excitation circuit of the intermediate-frequency amplifier 14 is such that a voltage fluctuation in the supply circuit 20 produces a current change in the winding 28 which tends to over-compensate the change effected on the focus of the beam by the accelerating electrode system in response to that fluctuation of the supply-circuit voltage. On the other hand, the voltage-current characteristic of the excitation circuit of the scanning amplifier 19' is such that the voltage fluctuation of the supply circuit 20 produces a current change in winding 29 which tends to undercompensate the variation effected on the focus of the electron beam by the accelerating electrode system in response to that voltage fluctuation. Further, the number of turns in each of the windings 28 and 29 are so related that the focusing system is caused to effect variations on the focus of the beam which substantially compensate variations effected thereon by the accelerating electrode system whereby the focus of the beam is maintained substantially constant for fluctuations of voltage of the supply circuit 20.

Thus it may be seen that, in accordance with the present invention, means are provided for connecting at least a portion of the beam-focusing system in series with at least one of the signal-translating stages of the receivers to cause the focusing system to have a voltage-focus characteristic so related to that of the accelerating electrode system that fluctuations in the voltage of the supply circuit cause the systems to effect substantially complementary variations in the focus of the electron beam. In the preferred embodiment, however, as illustrated in the drawing, a plurality of circuit means is provided for individually connecting the several windings of the focusing system with the common power-supply circuit.

While in accordance with the specific embodiment of the invention disclosed in the drawing and described above, an intermediate-frequency amplifier and a scanning amplifier have been included in the arrangement for connecting the focusing windings to the supply circuit to cause the focusing system to have a predetermined voltage-focus characteristic related to that of the accelerating electrode system, it is to be understood that the invention is not limited to such a combination. Obviously, others of the signal-translating stages included within the receiver may be used in order to give the focusing system the required voltage-focus characteristic.

In general, the concepts of this invention may be applied to any given receiver in the following manner: Connect a first winding of the beam-focusing system to the common power supply circuit by way of a circuit arrangement selected from the existing circuits of the receiver and having such a voltage-current characteristic that the first winding tends to overcompensate variations effected on the focus of the beam by the accelerating electrode system in response to voltage fluctuations of the supply circuit; connect another winding of the beam-focusing system to the supply circuit by way of another circuit arrangement selected from the existing circuits of the receiver and having such a voltage-current characteristic that the second winding tends to undercompensate variations effected on the focus of the beam by the accelerating-electrode system; and proportion the number of turns in each of the windings to obtain the total number of ampere turns required to focus the beam and to compensate exactly the changes effected on the focus of the beam by the accelerating electrode system.

While it is not intended to limit the invention to any specific circuit arrangement or circuit constants, the following are suitable for use in an embodiment of the invention using the specific circuit illustrated in the drawing:

30	Cathode-ray tube	----- Type 12AP4
	Voltage of supply-circuit 20 (average value)	117
	Operating potential of anode 26 (average value)	7,000
35	Total number of ampere turns of beam-focusing system (average value)	500
	Exciting current of beam-focusing windings (average value)	50 milliamperes
	Magnetic winding 28	turns 3333
	Magnetic winding 29	do 6667

Assuming that the voltage of the supply circuit 20 fluctuates between 110 and 120 volts, the total number of ampere turns required properly to focus the beam at minimum and maximum values of the supply circuit voltage are 450 and 550, respectively. The exciting current of the intermediate-frequency amplifier 14 has an average value of 50 milliamperes which varies between 40 and 60 milliamperes in response to the assumed voltage fluctuations of the supply circuit. The exciting current of the field-scanning amplifier 19' has an average value of 50 milliamperes which varies between 47.5 and 52.5 milliamperes in response to the voltage fluctuations of the supply circuit. Knowing the ampere turns required properly to focus the beam for the several values of supply-circuit voltage and knowing the current in the exciting circuits of the amplifiers 14 and 19' for these values of supply-circuit voltage, it may easily be determined that winding 28 should comprise 3333 turns and winding 29 should comprise 6667 turns. In such a circuit arrangement, the beam-accelerating electrode system and the beam-focusing system of the cathode-ray tube 25 effect substantially complementary variations on the focus of the electron beam in response to voltage fluctuations of the supply circuit 20 and thereby maintain the focus of the beam substantially constant.

While there has been described what is at present considered to be the preferred embodiment of this invention, it will be obvious to those skilled in the art that various changes and modifications may be made therein without departing from the invention, and it is, therefore, aimed in the ap-

pendent claims to cover all such changes and modifications as fall within the true spirit and scope of the invention.

What is claimed is:

1. A television signal-translating apparatus comprising, a cathode-ray signal-translating device, an accelerating electrode system for said device having a predetermined voltage-focus characteristic, a beam-focusing system for said device having a predetermined voltage-focus characteristic, a common supply circuit for said systems the voltage of which is subject to fluctuations, and a plurality of magnetic focusing windings included in said focusing system, the number of turns in each of said windings being such that the voltage-focus characteristics of said electrode system and said beam-focusing system are so related that fluctuations in the voltage of said supply circuit cause said systems to effect substantially complementary variations on the focus of said beam, whereby the focus of said beam is maintained substantially constant. 15

2. A television signal-translating apparatus comprising, a cathode-ray signal-translating device, an accelerating electrode system for said device having a predetermined voltage-focus characteristic, a beam-focusing system for said device, a common supply circuit for said systems the voltage of which is subject to fluctuations, a plurality of magnetic-focusing windings in said focusing system having predetermined current-focus characteristics, and a plurality of circuit means having predetermined voltage-current characteristics for individually connecting each of said windings with said supply circuit, the voltage-current characteristics of said circuit means and the number of turns in each of said windings being such that said focusing system is caused to have a voltage-focus characteristic so related to that of said electrode system that fluctuations in the voltage of said supply circuit cause said systems to effect substantially complementary variations in the focus of said beam. 20

3. A television signal-translating apparatus comprising, a cathode-ray signal-translating device, an accelerating electrode system for said device having a predetermined voltage-focus characteristic, a beam-focusing system for said device, a common supply circuit for said systems the voltage of which is subject to fluctuations, a plurality of magnetic focusing windings in said focusing system having predetermined current-focus characteristics, a corresponding plurality of signal-translating stages having predetermined voltage-current characteristics, and means for connecting each of said windings to said supply circuit through a corresponding one of said stages, the voltage-current characteristics of said circuit means and the number of turns in

each of said windings being such that said focusing system is caused to have a voltage-focus characteristic so related to that of said electrode system that fluctuations in the voltage of said supply circuit cause said systems to effect substantially complementary variations in the focus of said beam. 5

4. A television signal-translating apparatus comprising, a cathode-ray signal-translating device, an accelerating electrode system for said device having a predetermined voltage-focus characteristic, a beam-focusing system for said device having a predetermined voltage-focus characteristic, a common supply circuit for said systems the voltage of which is subject to fluctuations, signal-translating stages associated with said device having predetermined voltage-current characteristics, and means for connecting at least a portion of said focusing system and at least one of said signal-translating stages in series with said supply circuit, the voltage-current characteristic of said signal-translating stage being such that the voltage-focus characteristics of said electrode system and said focusing system are caused to be so related that fluctuations in the voltage of said supply circuit cause said systems to effect substantially complementary variations in the focus of said beam, whereby the focus of said beam is maintained substantially constant. 10

5. A television signal-translating apparatus comprising, a cathode-ray signal-translating device, an accelerating electrode system for said device having a predetermined voltage-focus characteristic, a beam-focusing system for said device, a common supply circuit for said systems the voltage of which is subject to fluctuations, a pair of magnetic focusing windings in said focusing system having predetermined current-focus characteristics, a signal-translating stage associated with said device having a predetermined voltage-current characteristic, scanning apparatus having a predetermined voltage-current characteristic for controlling a scanning operation of said device, means for connecting said translating stage and one of said windings in series with said supply circuit and for connecting said scanning apparatus and the other of said windings in series with said supply circuit, the voltage-current characteristics of said stage and said scanning apparatus and the number of turns in each of said windings being such that said focusing system is caused to have a voltage-focus characteristic so related to that of said electrode system that fluctuations in the voltage of said supply circuit cause said systems to effect substantially complementary variations in the focus of said beam. 15
